UNITED STATES PATENT OFFICE.

EMILE BOESCH, OF SAN FRANCISCO, CALIFORNIA.

SIDE AND CENTER LAMP AND REFLECTOR FOR STREET-CARS.

SPECIFICATION forming part of Letters Patent No. 283,693, dated August 21, 1883.

Application filed August 18, 1882. (No model.)

To all whom it may concern:

Be it known that I, EMILE BOESCH, a citizen of the United States, residing in the city and county of San Francisco, State of California, have made and invented certain new and useful Improvements in Side and Center Lamps for Street-Cars; and I do hereby declare that the following is a full, clear, and exact description of the same, reference being had to the accompanying drawings.

My invention relates to a certain novel construction of lamps specially adapted for street-cars and vehicles, both for center and side lights.

15 The improvements, as hereinafter fully described, have for their object simplicity of construction with effective illuminating power.

The following description fully explains the nature of my said improvements and the manner in which I proceed to construct, apply, and use the same, the accompanying drawings being referred to by letters and figures as follows—that is to say,

Figure 1 is a vertical transverse section 25 through the lamp-case and the chimney-top of a side lamp. Fig. 2 is a front view. These two views show the lamp set into the wood-work of the case. Fig. 3 is a horizontal section through the lamp on the line $y y$, Fig. 2. 30 Fig. 4 is a vertical section through the lamp-case when used as a center lamp. Fig. 5 is a detail section through the lower part of the chimney-top, showing the connection with it of the inner flame-protector. Figs. 6, 7, 8, 35 and 9 show details of the construction of the reflector. Figs. 10 and 11 show the manner of constructing the burner-socket.

W, Fig. 1, may represent the side or end portion of a car-body where the lamp is inserted. A is the conical reflector, forming the back of the lamp-case. C is the glass front, and D is a flange, by means of which the lamp is set and secured in place. This lamp is produced by the intersection of a conical reflecting-surface, A, with a globular glass front, formed of a hemisphere, C, to which the cone is joined at its largest diameter. The front is made, preferably, in parts or sections $c c$, set in metal sashes $d d$, as this construction is both 45 more economical, and also provides a door by fixing one section, C', on hinges $e e$.

The reflector A is formed of a back or body,

with a central aperture, B', to receive a bull's-eye, y, in the case of a side lamp, where the reflector is set up vertically, or to serve as an 55 outlet to the chimney-top when the reflector is used for a center lamp, where the reflector is set horizontally. Around the outer edge a rim, b', is turned up, and the reflecting-surface is then formed by laying and securing all 60 round against this inner face a number of metal segments, g g. These plates or facets g g are cut to fit closely together at the edges, and to cover the circle all round. In order to hold them properly in line and produce an even 65 surface, I turn down the edges along both sides, as shown at g², Fig. 9. Two plates can be thus pressed closely together without overlapping. The facets g g are of the proper length to fit in between the rim inclosing the central aperture, B', and the exterior rim, b', so that but little holding means is essential. They are held in place additionally, however, by means of the metal clips h¹ h², which are bent over the rim b' and the edge of the facets g g at the 70 outer end, and at the inner end they are supported by the circular flange b² on the rim surrounding the central aperture, B', substantially as shown in Fig. 7. These plates are corrugated, in order to increase the reflecting-surface. Any one or more of these 75 segments can be readily renewed when broken or defaced, and the reflecting-surface can be kept at all times clear and perfect. Such a surface is produced at small expense, and 80 the entire surface can be changed as often as required without requiring any repairs or changes in the lamp itself. This construction contributes both to the cheapness of manufacture and to the durability of the lamp. This 85 part of the lamp-case is set into the frame or body of the car or other surface to which the lamp is to be attached, so that nothing but the glass front projects and is seen beyond the wood-work. When used as a side lamp, this 90 is of advantage in giving an abundance of light at the end of the car, where the lamp is usually placed, to illuminate the fare-box at that point without requiring an additional lamp for the driver. To fasten it in such position I provide upon the cone, at a point just behind its line of junction with the glass front, a flat 95 projecting ring on the outside of the cone, so as to form a flange, D, through which fastening 100

nails or screws can be inserted to take into the wood-work beneath. Nothing but the front C of the lamp is therefore seen outside of the wood-work. This gives an unobstructed outlet for the rays around the sides of the lamp, and greatly increases the area of illumination, besides presenting a highly-ornamental appearance within the car. The greater portion of the base or socket is located outside the line of junction of the cone with the front, so as to bring the burner well forward. This construction is applicable to center lamps as well. In such case the cone-reflector A is made the top of the lamp, and the globe C, secured to it beneath, is provided with the socket F to hold the burner M.

In order to prevent the dispersion of light at the sides of the globe, and to concentrate and deflect the lateral rays downward, I carry out the edge of the cone A beyond the circle of intersection with the globe, so that a portion of the reflector is then outside of the body C. The sides of the cone A are therefore simply prolonged to project beyond the globe. This construction is clearly shown in Fig. 4 of the drawings. This lamp is suspended in the center from the roof of a car by means of arms or hangers G G, secured to the top of the cone A, at g' g', and having ears g² g², by which to fasten the hangers to points of support above the lamp. In a low-ceiling car the lamp can be inserted into the ceiling and secured by means of screws passed through the edge of the cone at n n, and the hangers 35 will not be required. From the central outlet, B', the chimney H leads up through the top of the car. The air for combustion is supplied through apertures m m in the bottom of the case.

In cases of exposure to high winds I produce complete protection of the flame from downward drafts by providing the chimney H with two channels, one a central outlet, h, placed immediately over and in line with the flame, and properly guarded by a cap or plate, h³, at the top to prevent the downward draft from entering, and the other an outer channel, h', surrounding the outlet h and leading directly into the interior of the lamp-case. The inner channel conducts the heat and gases of combustion away from the burner or lamp M, and in conditions of exposure to down drafts or gusts of wind it guards the outlet of the burner-chimney and keeps the flame clear 55 and steady. The outer channel at such time acts to lead the downward currents away from the burner-outlet, and they are then deflected and carried down to enter the burner through the usual apertures around the flame.

I prefer to make the inner tube, H', smaller at the top than at the bottom, so that it takes a conical shape. This gives the best form of channel both for the inlet h' and the outlet h. This construction of chimney produces a steady even light in the most exposed situations.

In the jolting and rough motion to which

car-lamps are subjected the oil that finds its way out from the burner and collects in the bottom of the lamp becomes frequently a source of annoyance and uncleanliness by dripping from the lamp-case, and I have found it desirable to provide a means of catching and collecting it within the socket. To accomplish this I make the socket F somewhat larger in diameter than the body of the burner M, and then fix on the outside of the burner-body, at intervals apart, three or more wires, s s, thick enough to fill the space between the burner and the inside of the socket-rim. These wires project below the bottom of the body and form legs to rest on the bottom of the socket, and when the burner is placed in position a clear space, t, is formed beneath it, that serves as an oil-collector or drip-cup. This also forms a simple and secure fastening for the burner, and is readily adapted to any form of burner and socket.

The advantages derived from these improvements are simplicity and cheapness of construction, with a highly-ornamental appearance, an increased area of illumination, particularly at the sides, and a steady clear light under all conditions of weather.

Having thus fully described my invention, what I claim, and desire to secure by Letters Patent, is—

1. A car-lamp having a conical reflector, A, and a globe front or body formed of sections c c, one of which is hinged to serve as a door, substantially as described.

2. The combination of the reflector A, the glass front formed of sections, one of which is hinged to serve as a door, and the rim or flange D at the intersection of the front with the reflector, substantially as described.

3. In a car-lamp, the combination, with the conical reflecting back A, adapted to be set into and be secured in the wood-work of the car, of the sectional glass front projecting from the rim of the said reflector, and having the lamp-socket extending outside of the zone or circle of intersection of the said reflector with the front, whereby the rays of light from the lamp or burner are brought forward into and thrown out at the sides of the front, as herein set forth.

4. In a lamp, a sectional globe-front having a back formed of a conical reflector attached to it at its largest diameter, substantially as described.

5. The combination, with the conical reflector A, having arms or hangers G G, of the sectional globe C, having the hinged section C', and the socket F for the burner, substantially as described.

6. The combination, with the reflector-body A, having the rim and fastening-clips, of the reflecting-surface formed of separate segment-plates g g, with turned-up edges g' to prevent the overlapping.

7. In a lamp, the combination, with the burner-body, of the legs formed of wires that are secured to the burner-body at intervals,

and are of such diameter with respect to the space provided between the burner and its holding cup or socket that they constitute both a support to hold the burner above the 5 socket-bottom and a fastening to fix the burner in place, as herein set forth.

8. The car-lamp consisting of a body formed by the intersection of a conical reflecting-surface, A, a globe-front, C, composed of sections 10 C' C, one of which is hinged to form a door, a socket, F, for the burner, and the double chimney H H', substantially as described.

9. In a lantern or lamp, the chimney H', provided with a cap, h³, in combination with an exterior chimney, H, surrounding the chimney H' and extending to a point above it and its superposed cap, and opening into the lamp-case, and with the lamp or other light, substantially as and for the purpose set forth. 15
